UNITED STATES PATENT OFFICE.

CHARLES A. BULL, OF ALBION, NEBRASKA.

PIN-HOLDER.

1,272,768.

Specification of Letters Patent. Patented July 16, 1918.

Application filed August 6, 1917. Serial No. 184,748.

To all whom it may concern:

Be it known that I, CHARLES A. BULL, a citizen of the United States, residing at Albion, in the county of Boone and State of Nebraska, have invented certain new and useful Improvements in Pin-Holders; and I do declare the following to be a full, clear, and exact description of the invention, such as will enable others skilled in the art 10 to which it appertains to make and use the same.

This invention relates to improvements in pin holders and particularly to that type used in combination with desk trays or the 15 like.

The primary object of the invention is to provide a device of this character which will positively clamp pins and dispose them within easy reach of the user.

Another object is to provide a device of 20 this character which, although extremely simple in construction and operation is highly efficient in its purpose.

With these and numerous other objects in 25 view, my invention resides in the novel features of construction and in the combination and arrangement of the several parts as described in the specification and claims and clearly illustrated in the accompanying 30 drawings which form a part of this application and in which:

Figure 1 is an end elevation of my improved pin holder.

Fig. 2 is a top plan view thereof.

Fig. 3 is a transverse sectional view on the 35 plane of line 3—3 of Fig. 2. Fig. 4 is a sectional view on the plane of line 4—4 of Fig. 3 and Fig. 5 is a sectional view on the plane of line 5—5 of Fig. 3.

The present embodiment of my invention 40 as illustrated in the accompanying drawings comprises a base 1 preferably molded from glass or the like, and, although shown in the form of a rectangular desk tray, may be of any preferred configuration. The desk tray, as illustrated, is provided in its upper face, at the front, with serrations or grooves 45 for the purpose of holding pens, pencils, etc., and, at a substantially central point, ink wells are disposed in suitable sockets.

The base is provided at its rear upper edge, with an upstanding rib 2, for many apparent purposes and for one purpose in particular which will be seen as the description progresses. At each end of the base,

near its lower edge and adjacent the side provided with the upstanding rib is a pivot socket 3 whose purpose will be described. Disposed adjacent the longitudinal flat side provided with the rib and parallel therewith 60 is a flat clamping plate 4 formed from spring metal and of a width substantially equal to the height of the adjacent side of the base, and having a laterally extending arm 5 at each end to be connected to the 65 adjacent end of the base in a manner to be set forth.

In connecting the clamping plate to the base, each arm is provided adjacent its lower outer edge with a depending ear 6, which is 70 in the same vertical plane with the arm, and which is provided with a central pivot stud 7 to be received in the adjacent pivot socket in the base, whereby the clamping plate may be swung outwardly and downwardly so 75 that a paper strip of pins 8 may be placed between the plate and the adjacent side of the base.

Spaced above the pivot sockets and vertically alined therewith are additional sockets 80 9 which are adapted to receive the detents 10 stamped from the arms at points near their upper edges. The clamping plate and arms, being formed from spring metal, provides 85 means for springing and positively retaining the pivot studs 7 in their sockets, and for retaining the plate in its clamping position, by springing the detents 10 into the sockets 9.

When the pins are in proper position the 90 heads are disposed above the upper edge of the rib 2, said upper edge being horizontally alined with that of the clamping plate whereby a firm gripping or clamping action is exerted on each of the pins. The clamping plate, it is to be understood, may be spaced 95 from the base a sufficient distance to permit a single strip of pins to be placed in position for clamping, or, to permit placing a whole paper package of pins therein.

It will be noted that this invention is extremely simple in construction and operation and it can therefore be made at a low cost, while at the same time it will effectively hold and dispense pins.

From the foregoing description, of the 105 construction and operation of my improved pin holder the operation thereof will be understood, and it is also to be understood, that within the scope of the appended claims, numerous changes in the minor details of 110

construction may be made without sacrificing the principal advantages.

I claim:

1. A device of the class described comprising a base having a substantially rectangular side, a flat clamping plate disposed adjacent said side of the base and having a pair of laterally extending arms on its ends to contact the opposite ends of said base, said arms being pivotally connected adjacent their lower edges to the adjacent ends of said base whereby the clamp may be swung outwardly and downwardly to receive a strip of pins between the plate and said side of the base.
2. A device of the class described comprising a base having a substantially rectangular side and a pair of sockets in its opposite ends adjacent the upper face of the base and said side, said base having a pair of

pivot sockets in its ends spaced vertically below the first named sockets, a flat clamping plate disposed adjacent said side of the base and having a pair of lateral arms on its ends, a pivot stud adjacent the lower edge 25 of each arm to be received in the adjacent pivot socket whereby the clamp plate may be swung outwardly and downwardly to permit placing strips of pins between said plate and side, and a detent stamped from each arm, adjacent its upper edge to spring into the adjacent socket in the base to retain the pins in position.

In testimony whereof I have hereunto set my hand in the presence of two subscribing 35 witnesses.

CHARLES A. BULL.

WARD MCKELLIP,
EDWARD P. LANGDON.
